UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,418,471.

Specification of Letters Patent. Patented June 6, 1922.

Application filed December 2, 1920. Serial No. 427,675.

To all whom it may concern:

Be it known that I, ALONZO E. RHOADES, a citizen of the United States, residing at Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms, whereby a change in the operative condition of the loom is effected when the filling in the shuttle becomes substantially exhausted.

The change in the operation of the loom which is effected by the feeler mechanism, may be, and usually is such as to replenish the filling in the shuttle prior to complete exhaustion, so that the loom may continue to operate to weave perfect cloth, or it may be that the feeler mechanism shall effect loom stoppage. Various forms of feeler mechanisms have been developed for effecting the change in the operative condition of the loom when the filling becomes substantially exhausted, and one of such types of mechanisms has comprised an impinging feeler and a penetrating feeler so that when the penetrating feeler was struck by the more dense substance of the filling carrier or bobbin on a detecting beat, it would effect loom stoppage. In this general type of penetrating feeler mechanism, the feeler is normally positioned so as to be struck by the filling on each detecting beat, and to sink into the filling as long as a working supply is present in the shuttle. In other words, the penetrating feeler has been normally held in active or operative position. The constant recurring penetration of the penetrating feeler into the filling is liable to injure certain kinds of filling, and it will happen at times that the shuttle will fail to be properly boxed on a detecting beat, with the result that the penetrating feeler is liable to strike the bobbin-holding jaws in the shuttle, or the hard wood of the shuttle itself. Should this occur, the penetrating feeler becomes dulled and its pointed end will be liable to more seriously injure the filling.

An important feature of the present invention consists in a feeler mechanism comprising an impinging and a penetrating

feeler, the latter of which is normally held inactive or inoperative so that it will not engage the filling on a detecting beat until the filling approaches substantial exhaustion and is then made active or operative to thereafter determine the condition of the filling in the shuttle. Thus the constant recurring penetration of the feeler during the normal operation of the loom with a working supply of filling is avoided, and injury to the feeler point, should the shuttle be improperly boxed, on a detecting beat, is obviated.

In the practical development of the broad feature of the invention, the penetrating feeler is normally held retracted relative to the impinging feeler, so that while the impinging feeler will engage the filling on each detecting beat, the penetrating feeler will fail to be engaged by the filling, and to move the penetrating feeler into its feeling position or project it, the present invention has provided a penetrating feeler projector which becomes effective to project the penetrating feeler when the filling has reached a predetermined degree of exhaustion on a detecting beat.

A good, practical form of the invention is illustrated by the accompanying drawings, wherein:

Figure 1 is a perspective view of the detecting or feeler side of the loom, certain of the loom parts being omitted for clearness of illustration;

Fig. 2 is a side elevation partly in section, showing the action of the feeler mechanism when a working supply of filling is present in the shuttle;

Fig. 3 is an enlarged sectional detail, showing the penetrating feeler moved into its active or operative position or projected when the filling has approached a predetermined degree of exhaustion;

Fig. 4 is a sectional detail on an enlarged scale, showing the action of the penetrating feeler in effecting replenishment of filling when the filling in the shuttle is substantially exhausted on a detecting beat;

Fig. 5 is an enlarged detached perspective view of portions of the feeler mechanism, showing more particularly the impinging and penetrating feelers and their associated mechanism;

Fig. 6 is a detached detail in side elevation of the bunter;

Fig. 7 is a detached detail of the penetrating feeler projector; and

Fig. 8 is a detached detail in plan view showing one good form of feeler carrier.

5 The term "substantial exhaustion of filling" is herein used to designate that degree of exhaustion of filling which dictates that a change of filling be effected without the production of a partial or mispick, or too 10 much waste.

The filling changing mechanism and its 15 associated details for effecting a change of filling in the shuttle when the feeler mechanism calls for such change, is not herein illustrated, because the particulars of such features form no essential part of the present invention, which is more especially directed to the feeler mechanism itself, and the filling replenishing mechanism is or may 20 be of usual type, well understood in the art.

The loom frame 1 may be of suitable construction for supporting the operating parts, and it has secured thereto the brackets 2, one at each side of the loom, for supporting 25 the transverse or rock shaft 3 which may likewise be of usual construction and operation. Rising from the rock shaft 3 is the arm 4 to which is pivoted at 5 the actuator 6, the rear end portion 7 of which is 30 adapted at times to be engaged by an operating member 8. In the present instance of the invention the rear end portion 7 of the actuator 6 is normally out of the path of movement of the operating member 8, which 35 may be conveniently formed as a part of the cam follower or a separate operating member movable therewith.

Pivotedly mounted on the stud 9 supported 40 by the bracket 10 rising from the loom frame is the transmitter 11, the arm 12 of which is provided with a pin 13 which underlies the actuator 6. The other portion of the transmitter 11 has adjustably connected to it the cam plate 14 having a cam member 15 45 through which extends the end portion 16 of an arm 17 pivotally mounted on a stud 18 for swinging movement in a direction toward and from the front of the loom. A spring 19 normally holds the arm 17 in its 50 rearward position. The mechanism thus far described may be of usual type, and the details thereof may be varied.

The lay 20 is provided with the usual shuttle-box 21 to receive the shuttle 22 in 55 which is supported the filling carrier or bobbin 23 having the filling or weft 24 wound thereon. The front wall of the shuttle-box in the present instance of the invention is provided with an opening 25 and the adjacent or front wall of the shuttle 22 is similarly provided with an opening 26 which is designed to register with the openings 25 when the shuttle is in the detecting box to permit the entrance of the feeler or feelers. 60

65 In the present instance there are two feelers,

one an impinging and the other a penetrating feeler, which are supported by a feeler carrier for movement toward and from the front of the loom. Feeler carriers as now generally known, consist either of a sliding 70 plate which is movable toward and from the front of the loom, or a swinging arm which is pivotally mounted on the loom frame. Either of these may be conveniently used, but in the present instance of the invention 75 the former is shown in the drawings.

Extending from the main portion of the loom frame is the frame or shipper-stand 77 having the arm 28 which is provided with a slot 29 to which is adjustably secured the 80 bracket 30. In the present instance of the invention the bracket 30 comprises a plate, Fig. 1, which may be secured on the arm 28 by a clamp or set screw 31. Mounted on the bracket or supporting plate 30 is the feeler 85 stand 32 which may be conveniently secured to the bracket or supporting plate 30 by the clamping bolts 33.

The feeler stand 32 is shown as having a cover plate 34 which may be secured to 90 the base portion of the feeler stand by screws or other holding means 35. A slot 36 in a portion of the feeler stand and cover plate permit adjustment of the feeler stand and the parts carried thereby toward and 95 from the front of the loom as usual in this class of devices.

Mounted for sliding movement toward and from the front of the loom on the feeler stand is the feeler carrier 37, the front end 100 portion of which is formed as a stem 38 about which is placed a spring 39, one end of which bears against a shoulder 40 at the front part of the feeler stand and the other part of which bears against a shoulder 41 on 105 the feeler carrier, the construction being such that the spring 39 normally holds the feeler carrier in rearward position with permissive movement frontwardly.

The feeler carrier 37 supports the impinging and penetrating feelers. In the present instance the impinging feeler is supported at the rear end portion of the feeler carrier 37 and comprises a blunt contacting surface which may engage the filling on a detecting 110 beat without injurious effect. The impinging feeler in the present instance comprises the rear end portion 42 of the feeler carrier and a cover plate 43 which may be appropriately secured to the part 42, the construction being such that the rear portion 42 of the feeler carrier and its cover 43 provide a chamber for the penetrating feeler. 115

Mounted between the part 42 and the cover plate 43 of the impinging feeler is the 120 penetrating feeler which comprises the slide 44 having a penetrating point 45. The rear end portion of the penetrating feeler is adapted to extend through the face portion 125 of the impinging feeler when the penetrat- 130

ing feeler is in active or operative position, but normally the penetrating feeler is held in retracted position so that on a detecting beat the penetrating point 45 will not engage the filling so long as a working supply of filling is present in the shuttle.

In the present instance the penetrating feeler slide 44 is provided with a recess 46, Fig. 5, in which is placed a spring 47, one 10 end of which bears against a pin 48 secured to the impinging feeler, and the other end of which bears against a shoulder 49 on the penetrating feeler slide, the effect being that the spring 47 normally holds the penetrating 15 feeler in retracted position relative to the impinging feeler, and with its point 45 frontward of the surface of the impinging feeler, the construction being such that under normal working conditions with a sufficient supply of filling, the impinging feeler will engage the filling on each detecting beat, but the penetrating feeler will fail to engage the filling and the point 45 thereof will not be exposed. It is desirable, however, when the 20 filling in the shuttle approaches substantial exhaustion, but prior to the occurrence of substantial exhaustion, that the penetrating feeler be moved to active or operative position to thereafter determine when the filling 25 is substantially exhausted and a change of filling is desirable. To effect movement of the penetrating feeler to active or operative position, the present invention provides that when the impinging feeler enters the shuttle 30 sufficiently far to indicate approaching substantial exhaustion, a penetrating feeler projector will become active to move the penetrating feeler rearwardly into its active or 35 operative position.

40 In the present instance the cover plate 43, the rear end surface of which forms part of the impinging feeler, is provided with upwardly-extending lugs 50, Figs. 1 and 5, in which is supported the stud or shaft 51, 45 which extends in a direction transversely of the feelers. Mounted for rocking movement upon the stud 51 is the bunter carrier 52, Fig. 6, which is provided with an opening 53 through which the stud 51 passes. The 50 bunter carrier 52 has adjustably secured thereto the bunter 54 which may be locked in adjusted position by a suitable lock nut 55. The lower end portion of the bunter carrier 52 is provided with a shoulder 56 55 against which bears one end of a spring 57, Fig. 5, the other end of which bears against a pin 58 extending through the lower portion 42 and the cover 43 of the impinging feeler, the construction being such that the 60 spring 57 normally bears against the front shoulder 56 of the bunter carrier, Fig. 6, and causes its rear shoulder 59 to rest against a stop 60 mounted on or formed as part of the feeler carrier, Figs. 3 and 4.

65 The upper portion of the bunter carrier

52 is provided with a bearing or opening 61, Fig. 6, in which is mounted the pin 62, Figs. 3, 4 and 5. One end of the pin 62 projects laterally from the bunter carrier, as indicated in Fig. 5, and on it is loosely 70 mounted the projector 63. The projector 63, which is shown detached in Fig. 7, has an elongated opening 64, through which the stud 51 passes, and below the opening 64 the projector 63 is provided with a projection or lip 65 against which normally bears the flange or front end portion 66 of the penetrating feeler slide 44.

Pivottally mounted on the pin 67 supported by the upwardly extending portions 68 of the cover plate 43, is the actuator 69 which has a downturned end portion 70 against which normally rests the frontward curved portion 71 of the projector. The actuator 69 is normally under the influence of a spring plunger 72 which may be conveniently supported on the feeler stand, Fig. 2. The spring plunger 72 may be formed as part of a stem 73 seated in a socket portion 74 on the feeler stand, and normally pressed downwardly by a spring 75. An adjustable stop 76 serves to limit the downward movement of the spring-pressed plunger. The front end of the actuator 69 has a fan-tail or notched portion 77, Fig. 2, which, when the actuator 69 is lifted from its full to its dotted line position, Fig. 2, and moved frontwardly, is adapted to engage the arm 16 of the lever 17 hereinbefore described, and to move it frontwardly to thereby effect 100 replenishment of filling.

The construction is such that when a working supply of filling is present in a shuttle on a detecting beat, as indicated in Fig. 2, the spring-pressed plunger 72, acting 105 upon the actuator 69, holds the downturned end 70 of the actuator against the rounded surface 71 of the penetrating feeler projector and the shoulder 65 of the projector will rest against the flange 66 of the penetrating 110 feeler slide 44, the pin 51 at such times acting as a stop to the contra-clockwise swinging movement of the projector. With the parts in the position described, the penetrating point 45 of the penetrating feeler will be 115 retracted with relation to the rear end impinging surface of the impinging feeler, and will not engage the filling on a detecting beat, so long as a working supply of filling is present in the shuttle. As the filling approaches substantial exhaustion, the impinging feeler will enter the shuttle further and further until finally, when the filling has reached a predetermined degree of exhaustion but prior to substantial exhaustion, the 120 bunter 54 will engage the front wall of the shuttle or some other fixed part on the lay, and swing the bunter carrier 52 about the stud 51 as an axis, thereby likewise turning the projector 63 about the same axis. Such 130

movement of the projector 63 causes the downwardly-extended portion 65 of the projector to act against the front portion 66 of the penetrating feeler 44 and move it rearwardly until the penetrating point 45 of the penetrating feeler extends beyond the rear end portion of the impinging feeler. This condition is represented in Fig. 3, wherein the filling is shown as approaching substantial exhaustion. As the filling continues to be withdrawn from the shuttle during the weaving operation, the penetrating point 45 will finally be struck by the more dense surface of the bobbin or falling carrier 23, with the result that the penetrating feeler will be moved frontwardly relative to the impinging feeler, thereby swinging the projector 63 about the pin 62 as an axis and acting through the downturned end 70 of the actuator to turn the actuator about the axis 67 and lift its front end portion 77 in position to engage the arm 16 and effect loom stoppage as the feeler carrier moves frontwardly. The position assumed by the parts when the penetrating feeler ascertains that the filling is substantially exhausted is indicated in Fig. 4, wherein it will be noted that the penetrating feeler has been pushed frontwardly relative to the impinging feeler 30 and has moved the projector 63 about its axis 62 as a centre, thereby placing the actuator 69 in operative position for effecting replenishment of filling.

Hereinbefore the impinging feeler has been described as formed by the rear end portions of the plates 42 and 43, through an opening in which the penetrating point 45 of the penetrating feeler is adapted to pass when the penetrating feeler moves into active or operative position. This construction is simple and well suited for mechanically working out the invention, but obviously the impinging feeler and penetrating feeler may be changed as to details, within the true scope of the actual invention.

When the impinging feeler is formed by the lower plate 42 which may constitute the rear end portion of the feeler carrier, and the plate 43, as hereinbefore described, the cover plate 43 may be secured to the lower plate 42 by screws 78, but these details of course may be varied within wide limits.

What is claimed is:—

1. A feeler mechanism for looms, comprising in combination, an impinging feeler and a penetrating feeler, means which normally holds the penetrating feeler from engagement with the filling on a detecting beat, a feeler projector for moving the penetrating feeler into the filling engaging position, a bunter for operating the projector and adapted to be actuated only upon the filling reaching a predetermined degree of depletion prior to substantial exhaustion, an

actuator which is moved into operative position by the projector when the penetrating feeler is moved frontwardly relative to the impinging feeler on a detecting beat, and means controlled by the actuator for effecting replenishment of filling. 65

2. A feeler mechanism for looms, comprising, in combination, an impinging feeler and a penetrating feeler, means which normally holds the penetrating feeler from engagement with the filling on a detecting beat, a feeler projector for moving the penetrating feeler into active position, means for causing the projector to project the penetrating feeler prior to substantial exhaustion, an actuator adapted to have movement of the penetrating feeler imparted thereto by the projector when the feeler is moved frontwardly relative to the impinging feeler, and means controlled by the actuator for effecting replenishment of filling. 70 75

3. A feeler mechanism for looms, comprising, in combination, an impinging feeler and a penetrating feeler, means which normally holds the penetrating feeler from engagement with the filling on a detecting beat, a feeler projector for moving the penetrating feeler into active position, means for causing the projector to project the penetrating feeler prior to substantial exhaustion, an actuator engaging the projector and adapted to be operated thereby when the projector is moved by frontward movement of the penetrating feeler relative to the impinging feeler, and means controlled by the actuator for effecting replenishment of filling. 80 85 90

4. A feeler mechanism for looms, comprising, in combination, an impinging feeler and a penetrating feeler, means which normally holds the penetrating feeler from engagement with the filling on a detecting beat, a feeler projector mounted for two movements, a bunter for effecting one of said movements when the filling approaches substantial exhaustion to actively position the penetrating feeler, means rendered effective when the penetrating feeler is moved relatively to the impinging feeler on the beat-up for imparting the other movement to the feeler projector, and an actuator which is rendered operative by the second movement of the projector for effecting replenishment of filling. 105 110 115

5. A feeler mechanism for looms, comprising, in combination, an impinging feeler and a penetrating feeler, means which normally holds the penetrating feeler from engagement with the filling on a detecting beat, a feeler projector mounted for rocking movement about different axes, means for imparting rocking movement of the projector about one of said axes when the filling approaches substantial exhaustion to thereby 120 125

actively position the penetrating feeler, means for imparting rocking movement of the projector about another of said axes when the penetrating feeler is moved relatively to the impinging feeler on the beat-up, and means for replenishing filling rendered effective when the projector partakes of its second rocking movement.

6. A feeler mechanism for looms, comprising, in combination, an impinging feeler and a penetrating feeler, means which normally holds the penetrating feeler from engagement with the filling on a detecting beat, a feeler projector which is mounted for two different movements, means for effecting one of said movements only when the filling approaches substantial exhaustion on a detecting beat to actively position the penetrating feeler, means between the penetrating feeler and projector for imparting the other movement to the projector when the penetrating feeler is moved forwardly by engagement with the dense surface of the filling carrier or bobbin, and means actuated through the projector when it partakes of its second movement to replenish the filling.

7. A feeler mechanism for looms, comprising, in combination, an impinging feeler and a penetrating feeler, means which normally holds the penetrating feeler from engagement with the filling on a detecting beat, a feeler projector operable to move the penetrating feeler into active position and adapted to yield under forward pressure of the penetrating feeler, a bunter for operating the projector to project the feeler and adapted to be actuated only after the supply of filling in the shuttle has reached a predetermined degree of exhaustion, an actuator operable by the projector upon movement of the penetrating feeler forwardly relative to the impinging feeler, and means under the control of the actuator for effecting replenishment of filling.

8. In a feeler mechanism for looms, the combination of an impinging feeler, a penetrating feeler, a spring normally holding the penetrating feeler in retracted position relative to the impinging feeler that the filling may not engage the penetrating feeler on a detecting beat, a projector for moving the penetrating feeler into position for engagement with the filling and adapted to yield under forward movement of the penetrating feeler relative to the impinging feeler, means for operating the projector to project the feeler only after the filling in the shuttle has reached a predetermined degree of exhaustion, and means operable by the projector to effect replenishment of filling when the projector is operated by forward movement of the penetrating feeler relative to the impinging feeler.

9. A feeler mechanism for looms, comprising, in combination, a feeler carrier, an impinging feeler and a penetrating feeler supported by the carrier, means which normally holds the penetrating feeler from engagement with the filling on a detecting beat, a bunter carrier pivotally supported by the feeler carrier, a projector pivotally mounted upon the bunter carrier and movable by the bunter carrier into position to project the penetrating feeler, a bunter for rocking the bunter carrier into position to project the penetrating feeler, means actuated by forward movement of the penetrating feeler relative to the impinging feeler to swing the projector about its pivotal mounting upon the bunter carrier, and means actuated by said swing movement of the projector to effect replenishment of filling.

10. A feeler mechanism for looms, comprising, in combination, a feeler carrier, an impinging feeler and a penetrating feeler supported by the carrier, means which normally holds the penetrating feeler from engagement with the filling on a detecting beat, a projector for moving the penetrating feeler to its projected position, a pin supported by the carrier and having the projector mounted thereupon for swing movement and for movement bodily relative to the pin, a bunter for rocking the projector into position to project the penetrating feeler, means actuated by forward movement of the penetrating feeler relative to the impinging feeler to move the projector bodily relative to said pin, and means actuated by said bodily movement to effect replenishment of filling.

11. A feeler mechanism for looms, comprising, in combination, a feeler carrier, an impinging feeler and a penetrating feeler supported by the carrier, means which normally holds the penetrating feeler from engagement with the filling on a detecting beat, a pivot pin supported by the carrier, a bunter carrier rockingly mounted on said pin, a projector for projecting the penetrating feeler rockingly mounted on said pin and movable bodily relative to the pin, a connection between the bunter carrier and projector to impart rocking movement of the former to the latter, a bunter for operating the bunter carrier to project the penetrating feeler, means actuated by forward movement of the penetrating feeler relative to the impinging feeler to move the projector bodily relative to said pin, and means actuated by said bodily movement to effect replenishment of filling.

12. In a feeler mechanism for looms, the combination of an actuator, an impinging and a penetrating feeler, a bunter carrier on the impinging feeler and mounted for

- rocking movement relative thereto, a projector carried by the bunter carrier and having a rocking movement about two different axes, one to project the penetrating 5 feeler and the other to position the actuator for replenishment of filling, and a train of mechanism operated by the actuator when positioned by said other rocking movement of the projector.
- 10 13. In a feeler mechanism for looms, the combination of a feeler slide mounted for movement towards and from the front of the loom, a penetrating and impinging feeler mounted on the feeler slide, a bunter carrier 15 mounted for swinging movement on the slide, a penetrating feeler projector having a pivotal movement with the swinging bunter carrier and a further swinging movement relative to the bunter carrier, an actuator normally tending to swing the projector about one of its axes and moved 20 against its normally acting force by the penetrating feeler when the feeler is moved

by engagement with the dense surface of the filling carrier, and means for replenishing filling. 25

14. In a feeler mechanism for looms, the combination of an impinging and a penetrating feeler, a bunter carrier which is displaced by frontward pressure upon it 30 when the filling is substantially exhausted, a spring normally acting on the penetrating feeler to hold it in retracted and non-filling engaging position, a penetrating feeler projector held frontward by the penetrating 35 feeler and moved rearwardly by the bunter, an actuator pivotally supported and having a part which is engaged and moved by the projector when the penetrating feeler engages the dense surface of the filling carrier 40 to swing the actuator into filling replenishing position.

In testimony whereof, I have signed my name to this specification.

ALONZO E. RHOADES.
